UNITED STATES PATENT OFFICE.

JAMES JACOBSEN AND PETER JACOBSEN, OF MENASHA, WISCONSIN.

DESIGN FOR A BUR-GRINDING-GRINDER FRAME.

SPECIFICATION forming part of Design No. 33,971, dated January 22, 1901.

Application filed December 26, 1900. Serial No. 41,176. Term of patent 7 years.

To all whom it may concern:

Be it known that we, JAMES JACOBSEN and PETER JACOBSEN, citizens of the United States, residing at Menasha, in the county of Winnebago and State of Wisconsin, have invented and produced a new and original Design for a Bur-Grinding-Grinder Frame, of which the following is a specification, reference being had to the accompanying drawings, forming part thereof.

Figure 1 is a side elevation showing our new design. Fig. 2 is an end elevation of the same, and Fig. 3 is a view of the same looking downward upon it.

As shown in the drawings, the leading features of our design consist of a bell-shaped pillar 1, having a narrow base-flange 2, arms 3 3', mounted upon the upper end of said pillar, extending outward upon opposite sides thereof and carrying journal-boxes 4 4', one upon the extremity of each arm, in which an emery-grinder shaft may be journaled, the journal-box 4' having a half-circle extension 5 projecting from one of its ears, which has a thickness in excess of its companion ear, and said extension having the emery-wheel-guard-supporting-rod-holding aperture 6. The pil-

lar 1 is circular in horizontal cross-section and is curved inward from its base to near its upper end. Projecting from the pillar, between its base and upper end and under the arm 3', is a work-supporting-table carrying bracket-arm 7, whose upper surface is at right angles with the vertical axis of the pillar.

This design is applicable to frames of emery-grinders for grinding the metallic burs of feed-grinders which comprise in their combination or operation an emery-wheel mounted for revolution above a table carrying bracket-arm.

Having thus described our invention, what we claim as new, and desire to secure by Letters Patent, is—

The design for a bur-grinding-grinder frame, as herein shown and described.

In testimony whereof we have signed our names in the presence of two subscribing witnesses.

JAMES JACOBSEN.
PETER JACOBSEN.
